Primary Examiner — Shawn T Gingrich*Assistant Examiner* — Bryan N. Melvin(74) *Attorney, Agent, or Firm* — Justin Lampel(57) **CLAIM**

The ornamental design for a sensor light bar controller, as shown and described.

DESCRIPTION

FIG. 1 is a perspective view of a sensor light bar controller showing the claimed design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of FIG. 4; and,

FIG. 9 is an enlarged view of FIG. 5.

The Dash-Dash broken line depict portions of the sensor light bar controller that form no part of the claimed design. The Dash-Dot broken lines in FIGS. 4-5 and 8-9 depict the boundaries of the enlargements that form no part of the claimed design.

1 Claim, 9 Drawing Sheets(56)
